UNITED STATES PATENT OFFICE.

BOYD W. ALLEN, OF BOSTON, MASSACHUSETTS.

ELECTRIC SWITCH.

No. 906,361.

Specification of Letters Patent.

Patented Dec. 8, 1908.

Application filed April 6, 1908. Serial No. 425,302.

To all whom it may concern:

Be it known that I, BOYD W. ALLEN, a citizen of the United States, residing in Boston, in the county of Suffolk and State of Massachusetts, have invented new and useful Improvements in Electric Switches, of which the following is a specification.

This invention relates particularly to that class of electric light switches in which a plurality of lamps—such as, for instance, are supported by the arms of an electric light chandelier or electrolier—may be manipulated in series, and in which one, two, or more of said lamps may be placed in circuit, 10 or all extinguished, by the rotation of a barrel which is operated by the manipulation of a knob or handle outside the chandelier.

The present invention comprises certain new and useful constructions and arrangements of parts whereby the switch is shielded and guarded from loose wires in the chandelier, whereby the barrel is stopped in its rotation at fixed points and short-circuiting prevented, and whereby the mechanism 25 is attached to the fixture.

The nature of the invention is fully described in detail below, and illustrated in the accompanying drawings, in which:

Figure 1 is a vertical section taken through 30 the central shell, or metallic globe of an electrolier, with my improved switch-mechanism illustrated in position in elevation, and with the switch open. Fig. 2 is a plan view of the under side of the switch-mechanism 35 removed. Fig. 3 is a horizontal section taken on line 3—3, Fig. 1, looking up. Fig. 4 is a front elevation of the porcelain shield or guard removed. Fig. 5 is a side elevation of the same, looking toward the left. Fig. 6 40 is a perspective view of the barrel removed.

Similar characters of reference indicate corresponding parts.

Reference numerals 10 and 11 represent 45 the two halves which constitute the central globe or case of the electrolier.

12 is the conduit containing the negative wire 13 and the positive wire 14 (the former leading to the switch) which connect with the source of electricity, and 15, 16 and 17 50 (the last illustrated in dotted lines) represent the pipes or branches which lead to the lamps. These tubular branches are, of course, each provided with a pair of wires, and of the wires which connect them with the switch, 18, 19 and 20 are negative wires connecting the switch with the lamps supported

by the tubular branches 15, 16 and 17 respectively.

The switch comprises a vertically disposed barrel, a porcelain guard provided with horizontal extensions at its lower and upper ends, a connection securing the upper end of the guard to the fixture, means connecting the lower end of the barrel to a rotative knob on the outside of the lower portion of the globe, 60 and means for stopping the rotation of the barrel and locking it at certain points.

The barrel 21 is metallic and comprises the circular and comparatively thick upper portion 22, the lower portion 23, smaller in diameter and provided with a horizontal hole 24, a sleeve 25 pinned at 26 to the portion 23 and provided with the flange 27 formed with four teeth 28 and concaved on its periphery between said teeth, the circular flange 29, 70 and three contact teeth 30, 31, and 32 (Figs. 1, 3 and 6) below described, the whole barrel being made in one integral piece. The barrel is mounted in a semicylindrical porcelain shield or guard, made in one integral piece, 75 and which comprises the curved upright wall 33, the circular upper end or top 34 provided with a horizontal overhang or flange 35, and the preferably substantially rectangular lower end or base 36 so disposed with relation to the upright portion as to provide horizontal flanges or extensions 37 and 38. The upper end or top 34 is bored to receive 80 and constitute a bearing for the portion 22 of the barrel, and the base or lower end 36 is bored to receive and constitute a bearing 85 for the portion 23 of the barrel between the flange 29 and the toothed portion 27, 28, said flange 29 resting on the upper surface of the base, and the toothed portion 27, 28 being 90 next and under the base.

Mounted on the upper end of the porcelain guard and properly insulated from the upper end of the barrel by a sheet or sheets of mica 39, is a metallic connection or holder 100 which comprises an internally screw threaded tube or pipe 40 (shown in Fig. 1 as partly broken out) which is supported by a screw 41 which extends down from the portion 42 of the fixture from which the pipes 15, 16, 17 105 radiate, the substantially flat circular portion 43 integral with the upwardly extending pipe 40 and disposed next and above the mica disk 39, a lip consisting of the downwardly extending portion 44 and the inwardly extending portion 45 (Figs. 1 and 3), and a downward extension 46 (Figs. 2 and 3)

which is screwed to the rear portion of the upright wall 33 of the porcelain guard by a screw 47. These parts 40, 43, 44, 45 and 46 constitute one integral piece or holder, and 5 sustain the guard by means of the screw 47 and the inturned portion 45 of the lip which extends under the flange 35, and thus the switch-mechanism connected with the guard is sustained vertically in position at its 10 upper end. The lower end 23 of the barrel extends into a tubular connection 48 which is made of insulating material and provided with a pin 49 which extends through the hole 24, and the said connection 48 extends down 15 through a suitable hole in the lower portion of the part 11 of the globe and is connected by a pin 50 with a handle or ball 51 which is adapted to be rotated by the hand, thus enabling the entire barrel to be rotated, for 20 the purpose below described.

The teeth 30, 31, 32 are formed on the barrel 21 by recessing the barrel between the portion 22 and the flange 29, and constitute contact-points for a series of spring-switches 25 or individual switches 52, 53 and 54. As the barrel is rotated by the handle 51 the spring-switch 52 is in the path of rotation of the contact-tooth 30; the spring-switch 53 is in the path of rotation of the contact-tooth 31, and the spring-switch 54 is in the path of 30 rotation of the contact-tooth 32. These switches 52, 53 and 54 are respectively in electrical connection with the negative wires 20, 18 and 19. A spring 55 bears on the portion 22 of the barrel, and is electrically connected with the negative-wire 13. These 35 springs are all secured to the porcelain guard by means of suitable screws or bolts 56 which extend into suitable openings 57.

In the drawing, the switch-mechanism is 40 illustrated as open, and the inner ends of the three switches 52, 53 and 54, which are preferably upturned as shown, are not in contact with the barrel, but are opposite the recesses 45 which are formed in order to produce the contact-teeth 30, 31 and 32. The spring 55 is in contact with the barrel during the entire 50 rotation thereof. To light one lamp of the electrolier, the barrel is rotated one quarter turn toward the right, thus bringing the tooth 30 under and into contact with the switch 52, and lighting the lamp in the branch 17. To light the lamps in two branches of the electrolier, the barrel is given another 55 quarter turn toward the right; thus bringing the tooth 31 under and into contact with the switch 53, lighting the lamp in the branch 15 in addition to that in the branch 17. To light all the lamps in the electrolier, another 60 quarter turn toward the right is given to the barrel, thus bringing the tooth 32 under and into contact with the switch 54 and lighting in addition to the others the lamp in the branch 16. Another quarter turn to the 65 right brings the recessed portion opposite all

the three switches, as in Figs. 1 and 3, extinguishing all the lamps. By rotating the barrel to the left the lamps are all lighted at once, and further rotation extinguishes them one at a time. It will be seen that although 70 the approaching edges of these three teeth are on different radii of the circle which corresponds to the circumference of the portion 32, their rear edges are in a longitudinal line, thus causing the tooth 30 to remain in contact with the switch 52 while the tooth 31 is in contact with the switch 53, and both teeth 30 and 31 to remain in contact with their respective switches while the tooth 32 is in contact with the switch 54. It is not necessary 75 that the spaces between the different teeth 30, 31 and 32 should be of the same width, that is, that they should each be one quarter of the circumference of the barrel, it being only necessary that the switches 52, 53 80 and 54 should be brought successively into contact with the teeth 30, 31 and 32 at some portion of the first quarter rotation, second quarter rotation, and third quarter rotation of the barrel from its position as illustrated 85 in Fig. 1, so that the switch 52 would be brought into contact with the barrel during the first quarter rotation thereof, the switch 53 during the second quarter rotation, and the switch 54 during the third quarter rotation, whereby first one light is lighted, then the second in addition to the first, then the third in addition to the first and second. Theoretically the spaces between the different 90 teeth would be equal, but practically it is advisable that the second tooth 31 should be reached a little later than the beginning of the next quarter turn, and the third tooth 32 a little later than the second quarter turn in order to prevent sparking, and hence in 95 practice, as well as in the drawings, the spaces between the teeth are not equal. Each tooth however is brought into contact with its switch at some time during the quarter turn, but before it is thus brought into 100 contact there is a short space between the front edge of the tooth and the switch which corresponds with it. If the spaces between the teeth were exactly one quarter the circumference of the barrel it is evident that 105 the teeth would successively be very nearly in contact with their switches before the corresponding quarter turns of the barrel, and sparking would result. It should be understood however that it is not claimed that the 110 lighting of the different lamps of an electrolier in rotation, or one, two and three in order, is new in itself considered.

Applied to the under side of the base 36 of the guard, is a spring which is secured there- 115 to by suitable screws 58, 59. This spring consists of the portion 60 whose end is secured to the screw 58 and which extends around the screw 59 and is bent to form the portion 61 which extends to the toothed 120

flange 27, 28 and is then bent at its opposite end into the portion 62 which bears against the flange. The teeth 28 on this flange are four in number and the spaces between them 5 correspond to the four positions in a single rotation of the barrel assumed when one, two or three spring-switches are in contact with their respective teeth, and when the switch is open. In these four positions therefore 10 the barrel is held firmly, whereby there is no danger of looseness or partial rotation which might produce short-circuiting.

The portion 33 of the shield or guard of porcelain or other non-conductive material 15 extends for between half and three-fourths the distance around the barrel, besides overhanging it at the top portion 35 and extending outward from the base at 37, 38, and thus it not only insulates the barrel to the ordinary degree or extent, but it effectually 20 guards it and protects it from loose wires in the electrolier.

Having thus fully described my invention, what I claim and desire to secure by Letters 25 Patent, is:—

1. In an electric switch of the character described, a rotative barrel provided with a plurality of teeth at different points of its circumference, a guard or shield of non-conductive material disposed around the rear and side portions of the barrel and above and below the operative portions of the switch, a series of switches mounted on the guard and extending into the paths of rotation of said 30 teeth, a forward horizontal extension integral 35

with the upper end of the guard, a plate mounted on said upper end and provided with an upwardly extending internally screw-threaded pipe, a downward extension rigid with said plate and adapted to be secured to the rear wall of the guard, and a lip extending downward from the front edge of the plate and inward under the forward extension which is integral with the guard, for the purpose set forth. 40

2. In an electric switch of the character described, a rotative barrel provided with a plurality of teeth at different points of its circumference, a guard or shield of non-conductive material disposed around the rear and side portions of the barrel and above and below the operative portions of the switch, a series of switches mounted on the guard and extending into the paths of rotation of said teeth, a flange rigid on the barrel below the guard and provided with teeth the spaces between which correspond in position with the individual switches in the series, and a spring whose free end bears against said flange and thereby locks the barrel yieldingly at the points in its rotation where one or more of the switches are closed or all are open, for the purpose set forth. 45

In testimony whereof I have signed my name to this specification in the presence of 50 two subscribing witnesses.
